United States Patent Office

Des. 198,191
Patented May 12, 1964

198,191

FONT OF TYPE

Howard W. Silsby III, Annandale, Va., assignor to Farrington Electronics, Incorporated, Alexandria, Va., a corporation of Massachusetts

Filed July 3, 1962, Ser. No. 70,786

Term of patent 14 years

(Cl. D64—12)

The figure on the drawing is a face view of a font of type showing my new design.

I claim:

The ornamental design for a font of type, substantially as shown.
